US00D955502S

(12) United States Design Patent (10) Patent No.: US D955,502 S
Thomas et al. (45) Date of Patent: * Jun. 21, 2022

(54) TOY

(71) Applicants: Darrell Thomas, Arden, NC (US);
Brett Ronald Banther, Lake Toxaway, NC (US)

(72) Inventors: Darrell Thomas, Arden, NC (US);
Brett Ronald Banther, Lake Toxaway, NC (US)

() Term: 15 Years

(21) Appl. No.: 29/695,594

(22) Filed: Jun. 20, 2019

(51) LOC (13) Cl. 21-01

(52) U.S. Cl.

USPC D21/539
